CLAIM

The ornamental design for a backpack with detachable fanny pack, as shown and described.

DESCRIPTION

FIG. 1 is a front left perspective view of a backpack with detachable fanny pack showing our new design;

FIG. 2 is an exploded view thereof;

FIG. 3 is a rear view thereof;

FIG. 4 is a left side elevational view thereof, the right side being a mirror image;

FIG. 5 is a top view thereof;

FIG. 6 is a frontal view thereof; and,

FIG. 7 is a bottom view thereof.

The broken lines shown throughout the views represent top stitching.
